UNITED STATES PATENT OFFICE.

JAMES SCRIPPS BOOTH, OF DETROIT, MICHIGAN.

HOOD LOCK.

Application filed March 24, 1924. Serial No. 701,567.

To all whom it may concern:

Be it known that I, JAMES SCRIPPS BOOTH, a citizen of the United States, residing at Detroit, in the county of Wayne and State 5 of Michigan, have invented certain new and useful Improvements in Hood Locks, of which the following is a specification.

This invention relates to hoods for automobiles. It is the object of the invention 10 to provide an improved hood lock which is controlled solely from the inside of the car. It has another object, to eliminate the unsightly hood fastenings which are ordinarily used.

15 When the car is an enclosed car, this hood lock serves absolutely to lock the motor against tampering with, providing the owner of the car locks the door when leaving same.

20 Another feature of the invention is that when the control device on the instrument board is operated, the hood is automatically sprung open; this will be more fully explained in the specification following.

25 In the drawings:

Fig. 1 is a side elevation of the forward part of the car showing the hood and some of the lock connections in dotted lines.

30 Fig. 2 is a view of the instrument board showing the control members for the hood mounted thereon.

Fig. 3 is a section taken on the line 3—3 of Fig. 2.

35 Fig. 4 is a side elevation of the lower portion of the hood and the hood sill strip or jamb.

Fig. 5 is a section taken on the line 5—5 of Fig. 4.

40 Fig. 6 is a longitudinal section through the hood wing jamb showing the sliding lock.

Fig. 7 is a section taken on the line 7—7 of Fig. 5.

45 Fig. 8 is a section taken on the same line showing the hood wing released.

Fig. 9 is a section taken on the line 9—9 of Fig. 5.

50 Fig. 10 is a section taken on the line 10—10 of Fig. 4.

Fig. 11 is a section taken on the line 11—11 of Fig. 5.

55 The radiator is designated *a*, the cowl *b* and the hood in general *C*. The hood wing is designated *c* and is provided with the usual louvres *d*. This hood is quite different from the conventional design as the rear

end of the hood is considerably to the rear of the dash, shown in dotted lines as *e*. The bottom line of the hood wing is considerably above the chassis sill bar contrary to the ordinary construction. The sheet metal that forms the cowl continues down to the sill bar and then runs forward below the hood wing forming what I call a hood sill *f* for want of a better name. The top of this sill is inset to form a hood wing jamb *h*. This jamb has the metal turned over into a loop *g* to form a lock guide for the sliding lock bolt *i*. This sliding lock bolt *i* is shown in dotted lines in Fig. 1 so that its relative length with respect to the hood will be apparent.

Now, referring to Fig. 4 it will be seen that this lock guide is provided with a pair of openings *j*; these are arranged to fit the beveled strikers *k* which are welded onto the inside of the hood wing. These strikers are provided with shoulders *m* as shown in Fig. 8. The strikers may be readily pushed in through the opening *j* and through the opening into the lock bolt *i*. This opening is beveled and consequently when the striker is pushed in, it serves to lift the lock bolt until the lock bolt drops behind the shoulder *m*. Thereupon the parts are securely locked as shown in Fig. 7 as the coiled tractile spring *n* tends to keep the lock bolt down at the bottom of the guide. A pull wire *o* is secured to the pin *p* at the center of the lock bar. This pin protrudes through the slot *q*, and the pull wire then runs rearwardly and upwardly through the flexible tube *r* to the instrument board, where a button *s* is located one on each end of the instrument board.

When one desires to open the hood he simply pulls on either button; this through the wire *o* pulls the sliding bolt backwardly until the inclined surface *t* engages the roll *u* as shown by the dotted lines of Fig. 6. This serves to lift the lock bolt in its guide against the resistance of the spring *n*. This lifting position is shown in the dotted lines of Fig. 6. This obviously lifts the latch bolt so that it clears the shoulder *m* of the striker. The flat springs *x* then thrust on the inside of the hood wing and forces the hood wing out, thereby automatically opening the hood when the control member on the dash is released.

It will be apparent from the above description that this form of hood lock has

numerous features. In the first place it is easily controlled from the dash with a single operation. The hood then opens automatically, which is a desirable thing in drawing up to a gasoline station or when a woman, for instance, desires to have access to the hood. Furthermore by having the control in the car, if the car doors are locked the hood is then absolutely locked against tampering and the motor is thereby protected.

Furthermore the locking devices are completely concealed and the ordinary unsightly hood clamps are completely eliminated.

What I claim is:

15. 1. In an automobile, the combination of a hood, provided with a swinging hood wing, a sill having a turned over portion forming a hood wing jamb and a lock-bolt guide, and a slideable lock bolt in said guide for providing a concealed lock for the hood.
20. 2. In an automobile, the combination of a hood provided with a swinging hood wing, a sill having a turned over portion forming a hood wing jamb and a lock-bolt guide, a slideable lock bolt in said guide for providing a concealed lock for the hood, means for yieldingly urging said bolt into locking position and means for releasing said lock bolt passing under the hood and the cowl to the interior of the car.
25. 3. In an automobile, the combination, a hood, provided with a swinging hood wing, a sill having a looped over piece of metal forming a hood wing jamb and a bolt guide, a sliding bolt in said guide, means urging said bolt into locking position said bolt and guide provided with openings, one or more beveled strikers projecting inwardly and secured to the hood wing and adapted to engage in said openings and to be caught by the bolt when the hood wing is swung against the jamb, and means for sliding said bolt to release said strikers.
30. 4. In an automobile, the combination of a swinging hood wing, a sill provided with a bolt guide running lengthwise of the sill, a spring-urged bolt of relatively great length guided therein, and a plurality of inwardly projecting strikers located on the inside of the hood wing arranged to drive into the bolt and lift the same to pass to locking position, and means by which the bolt may be slid in the guide lengthwise to release the strikers.
35. 5. In an automobile, the combination of, a swinging hood wing, a sill provided with a bolt guide, a bolt slideable in the guide, one or more strikers on the inside of the hood wing arranged to be caught by the bolt, means for moving the bolt to release the strikers, and means for automatically thrusting the hood wing out when the striker is released.
40. 6. In an automobile, the combination of,

a hood wind adapted to swing, a sill, means concealed behind the sill and hood wing for locking the hood wing thereto, means for releasing said lock, and means for automatically thrusting the hood wing out when the lock is released.

7. In an automobile, the combination of a swinging hood wing, a sill, a sliding lock bolt, a striker on the inside of the hood wing arranged to be caught by the lock bolt, means for sliding the bolt to release the striker and a spring for thrusting the hood wing outwardly, when the striker is released.

8. In an automobile, the combination of a swinging hood wing, a sill, a guide thereon, a bolt slideable therein provided with an inclined surface, a striker on the inside of the hood wing projecting inwardly and arranged to be caught by the bolt, a spring for drawing the bolt forward, means extending to the exterior of the car for drawing the bolt rearwardly, and a member which the inclined surface of the bolt strikes when drawn rearwardly to lift the bolt and release the striker.

9. In an automobile, the combination of a swinging hood wing, a sill, a bolt guide thereon, a sliding bolt, a spring stressing forwardly, a beveled striker on the inside of the hood wing arranged to be caught by the bolt, means by which the bolt may be drawn rearwardly, means which the bolt encounters when drawn rearwardly to raise the same and thus release the striker, and a spring on the sill bearing against the hood wing to automatically thrust the hood wing out when the striker is released.

10. In an automobile, the combination of a swinging hood wing, a sill provided with a bolt guide, a sliding bolt guided therein and also capable of a limited lifting movement therein, means for urging the bolt into locking position, an inwardly projecting striker supported on the inside of the hood wing and arranged to drive through the bolt to lift the same to pass to locking position, and means for sliding the bolt lengthwise and for lifting the bolt at the same time to release the striker.

11. In an automobile, the combination of a sill, a relatively long sliding bolt guided lengthwise of the sill adjacent thereto, a hinged hood wing provided with a plurality of inwardly directed strikers pointing inwardly in the general direction in which the free end of the hood wing swings, said strikers arranged to engage the relatively long sliding bolt and temporarily displace the same to pass to locking position, and means for manually sliding the bolt to release the strikers.

In testimony whereof I affix my signature.
JAMES SCRIPPS BOOTH.
